UNITED STATES PATENT OFFICE.

CHARLES V. JAMESON, OF CHICAGO, ILLINOIS.

EXPRESSION DEVICE FOR AUTOMATIC MUSICAL INSTRUMENTS.

1,367,262.

Specification of Letters Patent.

Patented Feb. 1, 1921.

Application filed October 10, 1917. Serial No. 195,667.

To all whom it may concern:

Be it known that I, CHARLES V. JAMESON, a citizen of the United States, residing at Chicago, in the county of Cook and State of Illinois, have invented new and useful Improvements in Expression Devices for Automatic Musical Instruments, of which the following is a specification.

This invention relates to the expression devices employed in auto-pneumatic musical instruments, for emphasizing or accenting selected notes or passages of a composition, and more particularly to a device of this kind which is controlled by the pedals of the 15 exhaust pumps or feeders.

It is one object of my invention to simplify the construction of such devices.

A further object is to so organize the apparatus that parts requiring regulation or 20 repair are easy of access.

In the accompanying drawings:

Figure 1 is a front elevation of the lower portion of a player piano embodying the improved accent device. Fig. 2 is a transverse 25 section on line 2—2, Fig. 1. Fig. 3 is a similar section on line 3—3, Fig. 1. Fig. 4 is a transverse section of a modified construction of the invention.

Similar characters of reference indicate 30 corresponding parts throughout the several views.

1 indicates the action wind chest of the instrument which may be of any suitable construction; 2 the usual exhausters or feeders, each having a return spring 3 and 4 the 35 pedals for operating them through appropriate connections 5, 6. Associated with each exhauster is an equalizer or bellows 7 having the usual function of maintaining a substantially uniform tension in the wind chest 1. The exhausters are supported on the rear side of the customary stationary board or frame 8 arranged transversely in the lower portion of the piano case, while 40 the equalizers are mounted on the front side of said board. As the exhausters, equalizers and accent devices are duplicated, a description of one set will apply to both.

Each equalizer has a suitable or well 50 known resistance spring 9 and communicates with the corresponding exhauster 2 by a port 10 formed in the board 8 and the fixed rear board 11 of the equalizer and controlled by the usual check valve 12 arranged 55 within the exhauster. In the movable board

of the latter is the customary air port 13 to the outer end of which the check valve 14 is applied. The parts thus far described are of ordinary construction. Preferably located upon the board 8 is a transverse 60 wind board or chamber 15 which connects with the action chest by a trunk or pipe 16 and with the equalizer 7 by a passage 17 formed in the upper portion of the board 8, the equalizer being in constant communication with the action chest. 65

Coöoperating with each equalizer is a valved air chamber 18. In its preferred form, this chamber is applied to the face of the movable board 19 of the equalizer and the outer wall 18^a of said chamber is fixed and connected with the fixed board 11 of the equalizer by ties or braces 20. The top and side walls of said chamber are flexibly connected with the movable board of the equalizer by ordinary bellows folds like those of the equalizer, producing practically a double pneumatic or bellows having the intermediate movable board 19 common to both. 70

The air chamber 18 communicates with the outer atmosphere by a port 21 controlled by a suitable valve 22 preferably applied to the outer side of the chamber. This valve preferably consists of a pallet hinged at its upper end and acted on by a 80 spring 23 which is adapted to hold it open under ordinary or normal pumping of the exhausters 2, but allows it to close wholly or nearly so, under a sudden thrust or abnormal impulse of the corresponding pedal. 85 The spring shown in the drawings consists of a resilient strip fastened to the back of the valve and projecting above its hinge, its upper end engaging under a hook 24 secured to the wall 18^a. This spring also 90 extends below the valve and is arranged to engage an adjustable stop or button 25 also carried by said wall, whereby the extent of the closing movement of the valve may be regulated, as desired. 95

Excepting the port 21 the chamber 18 is closed on all sides. To produce the most satisfactory results, the movable boards of this chamber and the equalizer should be of substantially the same area. 100

In the use of the apparatus, when the 105 pedals are operated in the ordinary manner to produce a normal air tension in the action chest 1, the pumping bellows 2 exhaust the air from it through the trunk 16, wind 110

board 15, passage 17, equalizer 7 and port 10. The air is at the same time exhausted from the equalizer whose complete collapse by atmospheric pressure is resisted by its 5 spring 9 in the usual manner. Under these normal pumping conditions, the automatic or check valve 22 of the air chamber 18 remains open, as shown in Fig. 2, its spring 23 having the requisite stiffness for this purpose. The atmosphere is therefore allowed 10 to enter the chamber 18 freely and act upon the outer side of the equalizer which thus performs the usual function without restraint. If, however, the performer gives 15 either of the pedals a sudden, abnormal thrust, the air is exhausted from the corresponding chamber 18 by the quick closing movement of the movable board 19 of the equalizer and the atmospheric pressure 20 thereupon overcomes the resistance of the spring 23 and completely or nearly closes the valve 22, according to the adjustment of the stop 25. The result is that the atmospheric pressure is momentarily shut off from 25 the chamber 18, preventing such pressure from acting on the equalizer. The ex- hauster therefore produces the maximum, unreduced air tension in the action chest, causing the usual striker-pneumatics of the 30 instrument to act with increased force and accenting the corresponding note or notes. If desired, several of such abnormal thrusts may be exerted upon the pedals in rapid succession to accentuate a series of notes, 35 as in bringing out a solo part. The moment the performer resumes normal pedaling, the valve 22 opens under the action of its spring, again bringing the equalizers into action and producing normal, reduced ten- 40 sion in the action chest.

This accenting effect is obtained solely by the abnormal impulses received by the pedals, dispensing with separate manually operated devices for this purpose.

45 It will be noted that both in accenting and in playing normally, the air is exhausted through the equalizers which have no internal or other valves.

The valves 22 of the chambers 18, being 50 applied to their outer sides, are readily accessible for adjusting or repairing them. If desired, these valves may be allowed to close fully in accenting, but it is preferable to prevent their complete closure by the use 55 of the adjustable stops 25, in order to produce a more resilient and agreeable pumping action.

The air chamber 18 is not necessarily in 60 the form of a bellows, as shown in Figs. 1, 2 and 3. If desired, it may be in the form of a rigid casing, as shown at 18^a, Fig. 4. As in the construction first described, this

casing or chamber has an air inlet port 21^a controlled by a valve 22^a.

Instead of arranging the air chamber on 65 the outer side of the equalizer, the chamber and the equalizer may be located on opposite sides of the fixed board 8^a, as shown in Fig. 5. In this case, the air chamber 18^b which is shown in the form of a bellows, is 70 provided with an air inlet port 21^b controlled by a valve 22^b. The movable board 18^c of this chamber is connected by one or more links 26 with the movable board 19^a of the equalizer 7^a, so that when the equalizer is collapsed more or less by a sudden pressure upon the pedals, the movable board of the air chamber is moved outward, momentarily exhausting the air from the chamber, closing the valve 22^b and rendering the 80 equalizer ineffective, as in the first described construction.

I claim as my invention:

1. In an autopneumatic musical instrument, the combination of a wind-chest, an 85 exhauster therefor, an equalizer having a movable wall and connected with said wind-chest and the exhauster, and an air chamber, said equalizer having its movable wall exposed to the air in said air chamber, said 90 air chamber having an inlet and a normally-open valve controlling said inlet and moved toward its closed position by the excess pressure on the outside of said air chamber over that on the inside thereof, under an abnor- 95 mal action of the exhauster.

2. In an autopneumatic musical instrument, the combination of a wind-chest, an exhauster therefor, an equalizer having a movable wall and connected with said wind- 100 chest and the exhauster, and an air chamber having an inlet, said equalizer being located between the exhauster and said air chamber and a normally-open valve controlling said 105 inlet and moved toward its closed position by the excess pressure on the outside of said air chamber over that on the inside thereof, under an abnormal action of the exhauster.

3. In an autopneumatic musical instrument, the combination of a wind chest, an 110 exhauster therefor, an equalizer in commun- 115 ication with the wind chest and the ex- hauster, an air chamber to the air in which the movable board of the equalizer is ex- posed, said air chamber having an inlet, an 115 automatic valve applied to said inlet, a spring tending to hold said valve open under the normal action of the exhauster, said spring being attached to the valve and pro- jecting beyond its free end, and an adjust- 120 able stop arranged to be engaged by the pro- jecting end of said spring.

CHARLES V. JAMESON.
